SNUBBER PLATE

John M. Moon, Evanston, Ill., assignor to Signode
Steel Strapping Company, Chicago, Ill., a corpora-
tion of Delaware

Application August 31, 1944, Serial No. 552,020

1 Claim. (Cl. 105—369)

2

1 My invention relates to snubber plates of the type secured to the floor or other fixed part of a car or other cargo carrier for controlling the movement of a shiftable load in the car. As is disclosed in detail in patent to Scales No. 1,920,917, dated August 1, 1933, it is old and well known in the art to prepare a load in unit form, preferably on skids or runners extending in the direction of movement of a car, and to connect to the load a flexible metal strap (e. g., one of the longitudinal load unit binders) which is movable forwardly and backwardly in the car with the load, such flexible strap being threaded through an opening in a snubber plate anchored in fixed position on the car so as to apply a braking or retarding effect on the movement of the strap and, in consequence, of the load.

It is the object of this invention to improve plates of this type whereby they may be more effective for applying a braking effect on the movement of the strap, and thus for controlling the movement of the load, and whereby the plates may be quickly and easily removed from the floor of the car after a period of use, and whereby there shall be substantially reduced likelihood of damage to the car by reason of the use of the plates and their removal after use.

It is another object of the invention to improve devices of this type in sundry details hereinafter pointed out. The preferred means by which I have attained my several objects are illustrated in the accompanying drawings, in which

Fig. 1 is a perspective view of one of my improved plates in position on the floor of a car;

Fig. 2 is a vertical sectional view taken substantially at the line 2—2 of Fig. 1; and

Fig. 3 is a view illustrating the preferred method of removing a plate from the car without danger of gouging holes in or otherwise injuring the floor of the car.

Referring now to the several figures of the drawing, in which corresponding parts are indicated by the same reference characters, 10 indicates the floor of a car having one of my improved snubber plates 11 secured thereto by means of drive-screws or nails 12 passing through suitable openings 13 through the plate, and serving to anchor the plate very strongly against longitudinal movement with respect to the floor of the car. Preferably the plates 11 are made from rather hard and tough steel having high resistance to wear, so as not to be unduly worn by the abrading action of the metal straps which thread through the slots thereof. In or-

5 der not to interfere with or injure the loads placed thereabove, these plates must be relatively thin. Likewise the anchoring action of the drive-screws or nails decreases as the thickness of the plates increases. I have found that a thickness of about one-eighth of an inch gives good results. Each plate 11 is provided with an elongated opening 14 therethrough, in the form of a slot parallel with one transverse edge thereof, for receiving a flexible steel strap 15 threaded through said opening and extending from the opening along the top and bottom face portions of the plate. The arrangement is such that the strap 15 is given an offsetting or snubbing bend 16 at the point where it passes through the slot 14. As will be readily understood and as is fully explained in said Scales patent above referred to, with the strap 15 connected with a load so as to move therewith and with the strap held in fairly 20 tight condition by its connection with the load, the plate 11 exerts a braking effect on the longitudinal movement of the strap so as to permit movement of the load along the face of the floor, and yet to resist or retard such movement 25 and act as a brake against excessive load shift. It has been found in practice that the arrangement as shown is very effective for controlling a load in a car so as to protect both the load and the car from damage so far as possible, and so 30 as to keep the load normally in its desired position in the end of the car and away from the space between the side doors at the middle portion of the car.

As is set forth in said Scales patent, the metal 35 straps, such as the strap 15, which are connected with the load sought to be controlled, are first threaded through the slots of the snubber plates 11 and laid out on the floor of the car over the space to be occupied by the load unit, after 40 which the plates 11 are firmly anchored in position on the floor by means of drive-screws or nails. The load is then placed in position over the straps, the straps are looped about the load unit, tightened to the desired degree and the 45 ends joined by a suitable seal-joint. If, as is frequently the case, the friction between the tensioned strap and the load is insufficient to prevent the strap sliding relative to the load, the strap may be anchored against such movement 50 in any appropriate manner. To give the best results there should be little, if any, slippage between the strap and the load. One satisfactory method is to thread the strap through an additional snubber plate, which, by nails or drive- 55 screws, is immovably attached to the load. Each

of the straps is thus brought into strong gripping engagement with the plate 11 through which it is threaded so as to give the plate a snubbing effect with respect to longitudinal movement of the strap and the load. When the load is to be removed from the car, the straps 15 are cut so as to leave the load free to be lifted away from the plate with the strap 15 still threaded therethrough.

After the load has been removed, it is necessary that the plate or plates 11 and the straps be removed from the car floor, and it has always been a rather difficult task to remove the plates quickly and easily without marring the floor of the car. For facilitating the removal of the plates, I have provided an upwardly offset portion 16 at an edge portion of the plate overlying the strap 15, so as to permit a claw 17, forming a part of a hammer or "wrecking bar," to be inserted between the strap and the plate, as shown in Fig. 3, for enabling the plate to be pried loose from the floor. With the heel of the claw device engaging a portion of the strap 15 for this operation rather than having its bearing directly on the wooden floor, the danger of breaking the surface of the floor by gouging holes therein is eliminated, the operator being able very easily to pry the plate loose by a pull longitudinally of the nails so as to accomplish the desired result without damage to the floor.

As will be appreciated from an inspection of Fig. 2 of the drawing, showing the parts in their operative positions, the longitudinal pull on the strap 15, as the load tends to shift and to carry the strap therewith toward either the right or the left in said figure, comprises a component acting upwardly on the portion of the plate immediately to the left of the slot 14 in said Fig. 2, tending to cause such portion of the plate to be gradually forced upwardly so as to reduce the snubbing effect on the strap. In order to guard against this tendency, I have pressed a rib in the plate in close proximity to the slot 14 so as to give an increased section modulus to the plate, for strengthening and stiffening the struc-

ture with respect to opposing upward or downward bowing of the metal. In the arrangement illustrated, the strengthening or stiffening of the plate in opposition to upward bowing is effected by carrying the upward offset portion 16 into close proximity to the slot 14, whereby such offset portions functions both as a stiffener to maintain the frictional and snubbing action upon the strap, and as a means for facilitating the use of a lever

10 for prying the plate loose.

While I prefer to employ the form and arrangement of parts as shown by my drawing and as above described, the invention is not to be limited to such form and arrangement except so far as the claims may be so restricted, it being understood that changes might well be made in the construction without departing from the invention.

I claim:

20 A snubber plate adapted to be attached securely to the floor of a car and having an elongated opening therethrough for engagement with a flexible strap for applying a braking effect on the longitudinal movement of the strap with respect to the plate, said plate being offset upwardly at an edge portion under which the strap normally extends in use for enabling a claw to be inserted on top of the strap and underneath the plate for prying the plate loose from the floor, with said upward offset of the plate extending into close proximity to said elongated opening through the plate so as to reinforce and stiffen the plate for increasing its resistance to distortion from upward pressure of the strap thereon.

JOHN M. MOON.
